United States Patent Office

Des. 200,311

Patented Feb. 16, 1965

200,311

COMBINED BELT BUCKLE AND COSMETIC KIT

Jack Lesser, 1030 Arboretum Road, Wyncote, Pa., and Leon H. Halber, 1109 Glenview St., Philadelphia 11,
Pa.

Filed Sept. 13, 1963, Ser. No. 76,578

Term of patent 14 years

(Cl. D17—1)

Fig. 1

Fig. 2

Fig. 3

Fig. 4

FIG. 1 is a front perspective view of a combined belt buckle and cosmetic kit embodying our new design;

FIG. 2 is a rear elevational view;

FIG. 3 is a side elevational view looking from the left of FIG. 2; and

FIG. 4 is a bottom plan view thereof.

We claim:

The ornamental design for a combined belt buckle and cosmetic kit, substantially as shown.
